PROCESS FOR DEWAXING MINERAL OILS

David G. Brandt, Westfield, N. J., assignor to
Cities Service Oil Company, New York, N. Y., a
corporation of Pennsylvania

Application May 11, 1938, Serial No. 207,232

4 Claims. (Cl. 196—18)

This invention pertains to a process for dewaxing petroleum oils, and more particularly to the dewaxing of petroleum lubricating oil stocks.

The invention of the present application is an improvement on the process of the applicant's pending application Serial No. 670,066, filed May 9, 1933, for improvements in the "Art of dewaxing oils." The said application discloses a process for dewaxing petroleum oil stocks to be used for lubricating purposes in which the stock is dissolved in a liquefied normally gaseous hydrocarbon diluent such as liquid propane or any similar hydrocarbon or mixture having less than five carbon atoms to the molecule. In that process a portion of the chilling is effected by vaporizing some of the solvent, although provision is made for mixing precooled diluent such as liquid propane with the oil solution at various stages of the chilling operation.

In carrying out the chilling process in accordance with the disclosure of said application, the oil-propane mixture is passed through a series of chambers and additional quantities of cold liquid propane is added to the mixture for the purpose of maintaining the desired gravity and viscosity of the oil mixture. After the precipitation of the wax in the oil solution, the wax is separated by gravity separation in an externally cooled separator in which provision is made for accelerating the removal of wax.

Repeated tests have shown that in the dewaxing of petroleum oils in which propane is used as a diluent and internal refrigerant, the chilling of the mixture by vaporizing propane apparently breaks up the wax crystals or prevents the formation of large wax crystals because of the intense agitation of the oil due to the vaporization of the propane.

Therefore, the primary object of the present invention is to provide an improved process for the use of a low molecular weight diluent such as liquid propane in which the wax precipitation will be greatly improved.

A further object of the invention is to provide an improved apparatus particularly adapted for carrying out the improved process of the present invention.

With these objects in mind the process of the present invention in general comprises the steps of forming a solution of the petroleum lubricating oil stock to be dewaxed in liquid propane or similar low molecular weight hydrocarbon, cooling the solution by indirect heat exchange with a cooler fluid to a point just short of wax precipitation in the solution, thereafter passing the

cooled solution into a chilling zone maintained at a pressure adapted to prevent vaporization of the diluent and introducing precooled diluent into the solution in sufficient quantity to effect the precipitation of all of the wax content of the oil desired to be removed therefrom, the introduction of the chilled diluent being effected in such a manner as to cause only a mild eddying of the oil mixture to bring it and the introduced diluent to equilibrium temperature conditions. After the wax has been precipitated in the manner described, it may be separated from the diluted mixture by settling, centrifuging or filtering, or any combination of these common practices.

Other objects, features and advantages of the process and apparatus of the present invention will be apparent to those skilled in the art from the following more detailed description thereof taken in connection with the accompanying drawing in which:

The single figure is a diagrammatic flow sheet of apparatus particularly adapted for carrying out the improved process, and in which certain of the elements of the apparatus are shown in vertical position.

Referring to the drawing, the oil stock to be dewaxed is conducted through a line 1, and introduced into a mixer 2 where the oil is mixed with liquid propane introduced through a line 3. A solution of the oil stock in propane is effected in the mixer 2 and the resulting solution is passed from the mixer downwardly through a heat exchanger column 4, first in indirect heat exchange with a cooling liquid such as water which is passed through a cooling coil 6, and then in heat exchange with a relatively cold liquid such as cold dewaxed oil which is passed through a heat exchange coil 8. The diluted oil stock introduced into the tower 4 may contain about 50% of liquid propane, and may be at an initial temperature of from 125° F. to about 145° F. or at the temperature of the solution leaving the mixer 2 in which the oil stock was brought into solution with liquid propane. In some cases particularly where the temperature of the oil or propane is too low, it is necessary to heat the oil or propane, or both, to the temperatures referred to, in order to effect thorough solution of the oil stock in the propane. The dilution at this point should not be greater than necessary to insure easy handling of the oil stock at temperatures approaching its pour point, or the point at which wax would begin to precipitate out. However, the oil mixture should contain at least 30% or 40% of propane at this stage of the operation.

The oil stock mixture passed through the cooling tower 4 is cooled to a temperature just above that at which wax precipitation would take place, and then conducted through a valved line 16 into a compartmented chilling chamber 12, in which vaporization of propane is prevented and in which the compartments are merely separated by baffles around which the oil mixture passes. As the oil mixture enters the first compartment, it is mixed with a proportion of cold liquid propane which is used exclusively as the cooling medium for precipitating the wax. As the oil mixture passes through the compartments of the chilling chamber 12 it is cooled to successively lower temperatures at any desired rate by the introduction of increments of extremely cold propane through a plurality of valved injection lines 14. In each compartment the cold propane is injected through an injector type of nozzle which prevents shock chilling by creating a flow of the oil mixture past the nozzle and by producing a gentle circulation of the mixture in each compartment. This method of injection insures thorough mixing of the cold propane and the oil stock mixture without causing any substantial agitation of the mixture which would tend to break up the wax crystals as they form.

Oil stocks which are more effectively handled by rapid chilling, may be chilled almost instantaneously in a single compartment of the chamber 12 or in a single chilling chamber, by rapidly mixing with the oil stock mixture the required amount of extremely cold liquid propane. The series of compartments in the chilling chamber 12 may be utilized to effect gradual chilling of the oil stock and the gradual building up of the wax crystals as the mixture advances through the chamber. The oil stock mixture in the chamber 12 may be cooled to a temperature of -20° to -40° F. or to any other temperature found to be necessary for completely precipitating the wax content desired to be removed from any selected oil stock under treatment.

The chilled oil mixture containing the precipitated wax in suspension is conducted from the chilling chamber 12 through a valved line 16, and forced by means of a pump 17, or passed through a valved by-pass line 18 and a line 19 into a wax separating apparatus 20 in which the wax is removed from the diluted oil mixture. The apparatus 20 may comprise any suitable wax separating equipment suitable for the particular stock such as centrifuges, filters, or settling chambers. The separated wax is conducted from the apparatus 20 through a line 22 into a wax washing unit 24, while the wax-free oil solution is conducted through a line 26 and passed by means of a pump 28 and a line 30 through the heat exchanger coil 8 mounted in the cooling tower 4.

While it is not necessary to maintain a super-atmospheric pressure on a propane oil solution at temperatures below about -40° F. to prevent vaporization of propane, substantial pressures are maintained on the oil mixture in the cooling tower 4, the chilling chamber 12 and the wax separating apparatus 20, in order to prevent any evolution of vapor. The pressure required in the cooling tower 4 and chilling chamber 12 will depend upon the temperature of the mixture as introduced into these chambers and must be sufficiently high to maintain the propane in liquid phase. Except for natural pressure drop due to flow resistance through these elements of the apparatus, the same pressure may be employed,

but a slightly lower pressure may be used in chamber 12. The valve in line 16 may be used to reduce the pressure a substantial degree, but where filter presses are used the pressure for effecting the filtration operation may be derived from the high pressure in the chamber 12 and tower 4 by-passing the pump 17.

The cold liquid propane used in effecting the chilling operation in the chamber 12 may be obtained by the auto-refrigeration of liquid propane initially at atmospheric temperatures. For example, liquid propane at atmospheric temperature is conducted from a propane storage 32, which of course will be maintained under suitable superatmospheric pressure to retain the propane in liquid state, through lines 34 and a series of indirect heat exchange coolers 36 and 38, and through a pressure reducing valve 40, into a propane chilling chamber 42. The expansion of the propane into the chamber 42 vaporizes a portion of the propane and chills the remaining portion; and the temperature to which the remaining liquid is reduced may be controlled by the pressure maintained in the chamber 42. The vapor evolved upon the pressure reduction in the chamber 42 is conducted through a valved line 44 and through the series of heat exchange coolers 38 and 36 by means of lines 46 and 48. The vapors evolved in the chamber 42 are naturally much cooler than that of the liquid propane prior to expansion, so that it is an ideal cooling agent for precooling the liquid propane in the coolers 36 and 38. The propane vapor in the line 48 is picked up by a compressor 50 which compresses the propane to a high superatmospheric pressure and forces it through a line 52, a condenser 54 and a line 56 into the propane storage 32. In this operation the pressure in the storage chamber 32 is maintained by the compressor 50. Propane from an outside source may be introduced into the system through a valved line 58 which connects into the line 52. A vacuum of any desired degree may be maintained on the propane chiller 42 by the suction created by the compressor 50, so that the liquid propane obtained in chiller 42 may have an extremely low temperature such as for example minus 55° F. to minus 85° F.

The cold propane distributed through the injection lines 14, is drawn from the chiller 42 through a line 60, and forced by means of a pump 62 and a valved line 64 into any or all of the lines 14 which may be in use for supplying cold propane to the oil stock mixture passing through the chilling chamber 12. Liquid propane from the chiller 42 may also be utilized in washing the oil from the wax in the washing unit 24 by merely withdrawing cold liquid propane from the line 64 through a valved line 66 which connects into the washing unit 24. The cold propane and oil washed from the wax in the unit 24 is removed through a valved line 68, while the washed wax is removed through a line 70. The cold oil-propane mixture from the line 68 may be introduced into any or all of the lines 14 and used as a chilling medium. The wax or wax slurry discharged through the line 22 is at a very low temperature and the cold liquid propane introduced through the line 66 is also at a very low temperature, so that the maintenance of substantial pressures in the wax washing unit 24 is not necessary.

In the dewaxing of many petroleum oil stocks, it is preferable to maintain the dilution of the stock as low as reasonably possible until the wax

precipitation is substantially complete, in order to insure the formation of relatively large wax crystals. Some stocks may not require very low temperatures in the chilling chamber 12 in order to precipitate the wax desired to be removed therefrom, but relatively low temperatures are usually necessary in order to prevent any rise in temperature above a certain maximum during the wax separation step. Minimum chilling for precipitation may be effected in the chamber 12 by the addition of extremely cold liquid propane, and the additional chilling necessary may be effected by conducting the oil stock mixture containing the precipitated wax from the line 16 through a connecting valved line 72 into a flash chilling chamber 74 in which the additional chilling is effected by vaporization of a portion of the liquid propane diluent under reduced pressure. In this operation, the vaporized propane is conducted from the flash chiller 74 through a valved line 76 into the line 44, and the chilled wax-stock mixture at the desired low temperature is conducted through a line 78 into the line 16 beyond the valve, and forced by means of pump 17 into the dewaxing apparatus 20. The temperature to which the oil stock is chilled in the chiller 74 is controlled by the pressure or vacuum maintained in this chamber, by regulating the valve in line 76.

Where it is necessary to chill the oil stock solution to extremely low temperatures for the precipitation of the wax content, a portion of the precipitation may be effected in the chilling chamber 12 and the remaining portion in the flash chiller 74 in order to avoid excessive dilution of the mixture during the wax precipitating operation. However, it is preferred to effect all of the wax precipitation in the chamber 12 under conditions such that there will be no agitation sufficient to break up wax crystals as is usually the case where propane vaporization is relied upon for chilling and precipitating purposes.

While various modifications may be made in the improved process and apparatus, as described above, the primary feature of precipitating the wax by addition of cold diluent has been found to materially increase the wax precipitation for a given chilling temperature and facilitate the separation of the precipitated wax. While liquid propane has been referred to as the diluent and chilling agent in the example, it is to be understood that other similar hydrocarbons or other compounds of low specific gravity may be employed, and the hydrocarbons may be saturated or unsaturated hydrocarbons preferably of lower molecular weight than butane.

It is to be understood that in utilizing the apparatus, all elements, lines and pumps will be insulated where the temperatures therein are below normal.

Having thus described the invention in its preferred form, what is claimed as new is:

1. In the process of dewaxing petroleum lubricating oil stocks in which the oil stock to be dewaxed is diluted with liquid propane in sufficient quantity to completely dissolve the oil stock and provide a solution which will be fluid and readily handled at temperatures below the pour point of the oil stock, the improvement which comprises cooling the solution by indirect heat exchange with a cooler low gravity liquid to a temperature just short of that of wax precipitation in the solution, thereafter passing the oil mixture to be dewaxed through a series of relatively large zones in which the mixture is gradually chilled to progressively lower temperatures by mixing there-

with precooled liquid propane under conditions adapted to prevent vaporization of any of the propane, introducing the cooled propane into the oil mixture in each zone in a jetting action 5 adapted to cause only mild eddying currents in each of said zones to effect equilibrium between the oil mixture and the introduced cold propane, maintaining a superatmospheric pressure in each zone and preventing substantial agitation therein, introducing a sufficient proportion of cold liquid propane into said zones to completely precipitate the wax content of the oil desired to be removed therefrom by the time the oil has passed through said series of zones, and separating the 15 precipitated wax from the resulting chilled oil mixture to produce a dewaxed petroleum lubricating oil stock.

2. The process of dewaxing petroleum lubricating oil stocks in which the oil stock to be dewaxed is diluted with a liquefied normally gaseous hydrocarbon which is liquid at low dewaxing temperatures, said hydrocarbon being used in sufficient proportion and under conditions such as to completely dissolve the oil stock and provide a solution which will be fluid and readily handled at temperatures at and somewhat below the pour point of the stock, thereafter passing the diluted mixture to be dewaxed through a series of relatively large chilling zones through 20 which the mixture is passed in series and gradually chilled by mixing therewith in each zone an increment of precooled liquid normally gaseous hydrocarbon, maintaining a substantial body of the mixture being chilled in each zone, introducing 25 the precooled liquid normally gaseous hydrocarbon into the oil mixture in each zone in a jetting action adapted to cause only a gentle local circulation of the mixture therein to effect equilibrium between the oil mixture and the introduced cold hydrocarbon, maintaining a superatmospheric pressure in each zone sufficient to prevent vaporization of any of said hydrocarbon and preventing substantial agitation in said zones, introducing a sufficient proportion of the cold 30 normally gaseous hydrocarbon into said series of zones to completely precipitate the wax content of the oil desired to be removed therefrom by the time the oil mixture has passed through said zones, and separating the precipitated wax from the 35 resulting chilled oil mixture to produce a dewaxed petroleum lubricating oil stock.

3. The process of dewaxing petroleum lubricating oil stocks in which the oil stock to be dewaxed is diluted with a liquid normally gaseous hydrocarbon which is liquid at wax separation 40 temperatures, diluting the oil stock with a sufficient proportion of said hydrocarbon and under such conditions as to completely dissolve the oil stock and provide a solution which will be fluid and readily handled at temperatures as low as the pour point of the stock, thereafter passing the solution to be dewaxed into one end of an enlarged elongated chamber and then through a series of distinct cooling zones in said chamber, maintaining a substantial body of the mixture 45 in each zone, gradually chilling the mixture as it passed through said series of zones in said chamber by mixing with the body of material in each zone an increment of extremely cold liquid normally gaseous hydrocarbon thereby gradually 50 building up wax crystals in the mixture as it advances through said chamber, introducing the cold hydrocarbon into the body of oil mixture in each zone in a manner adapted to cause only a 55 gentle local circulation of the mixture therein to

effect temperature equilibrium between the oil mixture and the introduced cold hydrocarbon, maintaining a superatmospheric pressure in said chamber sufficient to prevent vaporization of any of said hydrocarbon and preventing substantial agitation of the mixture in said chamber, said hydrocarbon introduced into said zones being of sufficiently low temperature and of sufficient proportion to completely crystallize and precipitate the wax content of the oil desired to be removed therefrom during the passage of the oil through said chamber, discharging the chilled mixture

from said chamber and separating the precipitated wax therefrom to produce a dewaxed petroleum lubricating oil stock.

5 4. The process of dewaxing petroleum lubricating oil stocks as defined by claim 3 in which said chamber is a vertical chamber and the solution to be dewaxed is introduced into the upper part thereof, and in which said zones are defined by vertically spaced baffles in said chamber around 10 which the oil mixture flows toward the bottom of the chamber.
